CATALYTIC DEHYDROGENATION PROCESS

Karl H. Hachmuth, Bartlesville, Okla., assignor
to Phillips Petroleum Company, a corporation
of Delaware

No Drawing. Application September 20, 1943,
Serial No. 503,151

6 Claims. (Cl. 260—683.3)

This invention relates to a process for dehydrogenation of saturated aliphatic hydrocarbons, i. e., paraffins to the corresponding olefins. More specifically, this invention relates to an improved process for the catalytic dehydrogenation of n-butane to produce butylenes. The improvement consists of initiating dehydrogenation at a high temperature and then lowering the temperature of the catalyst bed as the dehydrogenation cycle proceeds. The high initial temperature overcomes temporary initial poisoning of the catalyst and permits high yields of the desired dehydrogenation product, butylenes, while the activity of the catalyst is high. Lowering the temperature of the catalyst bed as the catalyst becomes deactivated reduces losses from thermal cracking and coking.

In conventional dehydrogenation the temperature is maintained at a substantially constant level. This constant temperature method offers several difficulties. If the temperature is held constant at a high level, excessive side reactions such as thermal cracking and coking occur. The higher the level at which temperature is maintained, the more pronounced is the occurrence of these undesirable reactions. For example, the amount of thermal cracking will approximately double for every 50° F. increase in temperature. These undesirable side reactions result in a decrease in the amount of feed stock available for recycle, thus reducing the ultimate yield (efficiency) of the process. In addition, these side reactions increase the hydrocarbon load which must be handled in subsequent separation steps. Another disadvantage of high temperature operation is that the coking apparently causes more rapid deactivation of the catalyst due to the increased deposition of carbon on the surface of the catalyst. If the temperature is held constant at a low level (low temperature for dehydrogenation of n-butane being anything below 1100° F.), temporary initial catalyst poisoning is evident. This poisoning is apparently due to moisture adsorbed on the surface of the catalyst during the regeneration cycle. If dehydrogenation is carried out at high temperatures, this moisture is removed so rapidly that no harmful effects are evident. However, at low temperatures removal of the poisoning is much slower and as a result the initial yield of the desired dehydrogenation product is lower than at subsequent points during the dehydrogenation cycle. Since the yields should be greatest at the beginning of the dehydrogenation cycle when the activity of the catalyst is at its peak, it is evident that the yields ob-

tained from low temperature dehydrogenation are lower than those for the high temperature process wherein temporary initial catalyst poisoning is quickly removed.

It was found that by beginning the dehydrogenation cycle at a high temperature and then slowly lowering the temperature as the catalyst became deactivated, it was possible to obtain both high yields and high efficiencies. The results were exactly opposite to results which were expected on the basis of conventional methods and fundamental chemical reactions. Since dehydrogenation is an endothermic reaction, and endothermic reactions are favored by the addition of heat, it would appear that the temperature should be raised not lowered in order to maintain a satisfactory yield as the activity of the catalyst declined. However, this was not the case as shown by this improved dehydrogenation process. Thus this process constitutes something new and unanticipated by workers in the field of catalytic dehydrogenation.

The process of this invention is advantageous since high yields can be obtained without sacrificing efficiency. Another advantage of this invention is the removal of temporary initial catalyst poisoning by means of the high temperatures used at the beginning of the dehydrogenation cycle.

In this process it is possible to obtain increased yields of the desired product while the activity of the catalyst is high by operating at initial temperatures which are sufficiently high to shift the thermodynamic equilibrium and thus increase the extent of dehydrogenation. This is possible since the dehydrogenation reaction is endothermic in nature and therefore is favored by the addition of heat. When the activity of the catalyst is high, thermodynamic equilibrium is apparently the factor which limits the extent of dehydrogenation. Thus at higher temperatures, it is possible to effect increased dehydrogenation by a favorable shift of the thermodynamic equilibrium. However, as the catalyst becomes deactivated, apparently other factors than the thermodynamic equilibrium tend to limit the extent of dehydrogenation and thus it is possible to dehydrogenate only that per cent of the n-butane feed stock determined by these limiting factors. For example, if some factor such as diffusion limits the dehydrogenation to 25 per cent, then no matter if the temperature is raised to a point corresponding to 50 per cent dehydrogenation, the yield will still be only 25 per cent. Since the high temperature can no longer ef-

fect increased yields by shifting the equilibrium but can effect increased thermal cracking and coking, such high temperatures are no longer desirable.

One object of this invention is to offer a means for catalytic dehydrogenation of saturated aliphatic hydrocarbons. Another object of this invention is to disclose improvements in a process for the dehydrogenation of n-butane to produce butylenes. Still another object is to obtain as high yields of butylenes as are obtained in higher temperature dehydrogenation without sacrificing the efficiency of the process. Still another object of this invention is to effect a shift of the thermodynamic equilibrium by means of high initial temperatures and thus take advantage of the endothermic nature of the dehydrogenation reaction while catalyst activity is high, in order to obtain higher yields of the desired product, butylenes. Still another object of this invention is to remove temporary initial catalyst poisoning by means of the higher temperatures used at the beginning of the dehydrogenation cycle.

In accordance with the present invention, the catalytic dehydrogenation of paraffins to olefins is accomplished by contacting the paraffin with a dehydrogenation catalyst under conditions which effect dehydrogenation of the paraffin to the corresponding olefin. The treatment is initiated at a relatively high temperature and as the dehydrogenation proceeds the temperature is lowered. The treatment may be carried out by passing a stream of the paraffin preheated to a suitable temperature through a bed of solid dehydrogenation catalyst the temperature of which is controlled in any suitable manner. Alternatively a "fluid" catalyst may be used. The paraffin is usually relatively low-boiling, i. e. having at least two but not more than six carbon atoms, these being ethane, propane, normal butane, isobutane, normal pentane, neopentane, isopentane and the several hexanes. Normal butane is the principal paraffin dehydrogenation stock in the present state of the art.

The temperature at the beginning is sufficiently high to overcome the temporary initial poisoning of the catalyst and give high yields while the activity of the catalyst is high. As the dehydrogenation proceeds and the catalyst becomes gradually deactivated, the reaction temperature is gradually, and preferably proportionally, lowered by any suitable means within the skill of the art at such a rate as to minimize losses of hydrocarbon feed stock by thermal cracking and coking.

In a preferred embodiment normal butane is dehydrogenated over a catalyst composed of alumina impregnated with chromium and magnesium oxides with the temperature initially at 1160° F. and the temperature is reduced at the rate of 1° F. per minute for one hour. The dehydrogenation is then discontinued, the catalyst regenerated and the process repeated. The temperature referred to is the external tube wall temperature of 2 inch ID (inside diameter) tubes.

EXAMPLE

In dehydrogenation of n-butane to butylenes using the improved process of this invention, a stream of n-butane is introduced into the catalyst case which is heated initially to about 1160° F. The catalyst case comprises 2 inch ID tubes filled with the granular catalyst. Then the temperature is lowered at a rate of approximately 1° F. per minute so that by the end of the one hour

cycle, during which dehydrogenation occurs, the temperature is approximately 1100° F.

The following table contains some data on the improved dehydrogenation process of this invention. For purpose of comparison, data for both low and high constant temperature dehydrogenation processes are included.

Table

Temperature F. ¹	Average pressure ²	Space velocity ³	Initial per cent con- version to butylenes	Per cent conversion to buty- lenes per pass	Effi- ciency
Improved Dehydrogenation Process					
1163-1095.....	22.4	633	43.5	34.01	80.43
Low Temperature Dehydrogenation Process					
1099-1101.....	19.8	502	27.2	27.43	83.35
High Temperature Dehydrogenation Process					
1155-1149.....	20.4	522	42.00	33.95	78.75
1192-1185.....	22.6	630	41.30	31.95	59.88

¹ This is the average temperature of the external wall of the catalyst tube.

² Average pressure in pounds per square inch absolute.

³ Space velocity in cubic feet, at standard conditions, of n-butane per hour, per cubic foot of catalyst.

The dehydrogenation was carried out during one hour cycles using a catalyst composed of alumina impregnated with chromium and magnesium oxides. The temperatures were measured on the external wall of the catalyst tube. However, actual internal temperatures of dehydrogenation bear a direct relation to these external wall temperatures. The temperatures given apply to 2 inch ID tubes. Pressure, space velocity, and catalyst activity were maintained at substantially the same levels. However, due to the difference in completeness of catalyst regeneration, it was not possible to return the catalyst to identical activity in each case. A comparison of the initial yield of 27.2 per cent butylenes and the total per pass yield of 27.43 per cent shows the effect of initial catalyst poisoning on the yield in low temperature dehydrogenation.

A comparison of the efficiencies for the two high temperature cycles shows the effect of increased temperature on the efficiency. At around 1150° F. the efficiency was 78.75 per cent, while at approximately 1190° F. it was only 59.88 per cent. On the other hand, comparison of the yields indicates that the additional heat resulted in increased destruction of feed stock without giving increased yields of butylenes.

By comparison, it can be seen that the yield of butylenes, 34.01 per cent, in the improved process was higher than that of the conventional processes, namely 27.43 per cent, 31.95 per cent, and 33.95 per cent, while the efficiency was 80.43 per cent for the improved process as compared with 59.88 per cent and 78.95 per cent for the high temperature cycles and 83.35 per cent for the low temperature cycle.

Thus it is evident that by means of this improved process for catalytic dehydrogenation of saturated hydrocarbons, a good yield can be obtained while maintaining the efficiency of the process at a high level. In addition, loss of hydrocarbon feed stock through coking and thermal cracking is reduced; the effect of temporary

initial catalyst poisoning is eliminated; and full advantage is taken of the initial activity of the catalyst to obtain higher yields of butylenes from each dehydrogenation cycle.

Although the dehydrogenation of n-butane to butylenes has been used for illustrative purposes in the preceding discussion, the process of this invention is not limited to dehydrogenation of n-butane to butylene but may be applied to the dehydrogenation of other paraffins to the corresponding olefins.

Also, the particular initial temperature and rate of temperature drop used as an example of the improved process are not necessarily the best values. Choice of the optimum conditions will depend upon the nature of the catalyst used and upon characteristics of the dehydrogenation equipment itself. Such optimum conditions must be found by experiment.

While the temperatures given herein were measured on the external walls of 2 inch ID tubes, it will be understood that catalyst tubes of any desired diameter may be employed in carrying out the process of the present invention. In the case of tubes of a different size, slight variations from the temperatures given may be employed as found desirable. It is also to be understood that the invention is not limited in its application to the use of a catalyst case comprising tubular catalyst chambers but is applicable with appropriate modification to any form of catalytic dehydrogenation equipment. The selection of suitable types and sizes of equipment, temperature and other operating conditions will be obvious to those skilled in the art in the light of this disclosure.

I claim:

1. A process for catalytically dehydrogenating paraffins to olefins which comprises contacting the paraffin with a dehydrogenation catalyst under conditions effecting dehydrogenation of said paraffin to the corresponding olefin, initiating said treatment at a high temperature, and as said dehydrogenation proceeds and said catalyst gradually becomes deactivated gradually lowering said temperature from the beginning to the end of the on-stream period.

2. A process for catalytically dehydrogenating paraffins to olefins which comprises contacting the paraffin with a dehydrogenation catalyst under conditions effecting dehydrogenation of said paraffin to the corresponding olefin, initiating said treatment with said catalyst at a high temperature such as to overcome temporary initial poisoning of said catalyst and to give high yields while the activity of the catalyst is high, and as said dehydrogenation proceeds and said catalyst gradually becomes deactivated gradually lowering said temperature from the beginning to the end of the on-stream period at such a rate as to minimize losses of hydrocarbon feed stock by thermal cracking and coking.

3. A process for catalytically dehydrogenating normal butane to butylenes which comprises passing a stream of normal butane through a bed of dehydrogenation catalyst and thereby dehydrogenating said normal butane to butylenes, initiating said treatment with said catalyst at a high temperature, and as said dehydrogenation proceeds and said catalyst gradually becomes deactivated progressively lowering said temperature from the beginning to the end of the on-stream period.

4. A process for catalytically dehydrogenating normal butane to butylenes which comprises passing a stream of normal butane through a bed of dehydrogenation catalyst and thereby dehydrogenating said normal butane to butylenes, initiating said treatment with said catalyst at a high temperature such as to overcome temporary initial poisoning of said catalyst and to give high yields of butylenes while the activity of the catalyst is high, and as said dehydrogenation proceeds and said catalyst becomes gradually deactivated gradually lowering said temperature from the beginning to the end of the on-stream period at such a rate as to minimize losses of hydrocarbon feed stock by thermal cracking and coking.

5. A process for catalytically dehydrogenating normal butane to butylenes which comprises passing a stream of normal butane through a bed of solid dehydrogenation catalyst and thereby effecting catalytic dehydrogenation of said normal butane to butylenes, carrying out said dehydrogenation with said catalyst initially at a temperature of about 1160° F. and as soon as said dehydrogenation is initiated progressively lowering said temperature from the beginning to the end of the on-stream period at a rate of approximately 1° F. per minute, continuing in this manner for approximately one hour, then discontinuing said dehydrogenation, regenerating said catalyst, and repeating said process.

6. A process for catalytically dehydrogenating normal butane to butylenes which comprises passing a stream of normal butane through a bed of solid dehydrogenation catalyst composed of alumina impregnated with chromium and magnesium oxides and thereby effecting catalytic dehydrogenation of said normal butane to butylenes, carrying out said dehydrogenation with said catalyst initially at a temperature of about 1160° F. and as soon as said dehydrogenation is initiated progressively lowering said temperature from the beginning to the end of the on-stream period at a rate of approximately 1° F. per minute, continuing in this manner for approximately one hour, then discontinuing said dehydrogenation, regenerating said catalyst, and repeating said process.
